DESIGN FOR LEATHER

Mabel Winkel, New York, N. Y.

Application September 3, 1938, Serial No. 79,737

Term of patent 3½ years

To all whom it may concern:

Be it known that I, Mabel Winkel, a citizen of the United States, residing at New York, New York, have invented a new, original, and ornamental Design for Leather, of which the following is a specification, reference being had to the accompanying drawing, forming a part thereof.

Fig. 1 is a plan view of a piece of leather showing my new design;

Fig. 2 is a sectional view on a somewhat enlarged scale on the line 2—2 of Fig. 1.

Fig. 3 is an enlarged face view of the present design.

Fig. 4 is an enlarged sectional view taken on line 4—4 of Fig. 3.

The dominant feature of the present design resides in spaced rows of short slits, each slit being bordered by a pair of protruding lips.

I claim:

The ornamental design for leather, substantially as shown and described.

MABEL WINKEL.
